UNITED STATES PATENT OFFICE.

MARTIN L. WILLIAMS, OF SOUTH BEND, INDIANA, ASSIGNOR TO J. W. CLEAVELAND, OF CHICAGO, ILLINOIS.

MANIFOLD FOR MOTOR-CARS.

1,239,424.

Specification of Letters Patent.

Patented Sept. 4, 1917.

Application filed May 31, 1913. Serial No. 770,915.

To all whom it may concern:

Be it known that I, MARTIN L. WILLIAMS, a citizen of the United States, residing in the city of South Bend, county of St. Joseph, and State of Indiana, have invented certain new and useful Improvements in Manifolds for Motor-Cars, of which the following is a specification.

This invention relates to improvements in manifolds for motor cars and has among its salient objects to provide a construction in which the heat units of the exhaust gases are utilized to vaporize the fuel in the inlet manifold instead of in the carburetor where by the fresh fuel is exposed to a maximum vaporized surface and before it enters the cylinders; to provide a construction in which the vaporized gases pass directly to the cylinders and are not subjected to the condensing action of a relatively cold inlet manifold as in the prior constructions; to provide a construction in which the relatively cool fuel and air are first mixed in the carburetor and then vaporized completely in the inlet manifold just before the gases enter the cylinders; to provide a construction in which the exhaust gases by reason of their heat units being utilized as aforesaid are delivered from the exhaust manifolds at a relatively low temperature, thus tending to eliminate the noise and reduce the back pressure; to provide a construction in which the inlet and exhaust manifolds are preferably made in a single casting, thus reducing the cost of manufacture and making a more simple construction; to provide a construction which is adapted for use with any of the well known engines used on motor cars; to provide a construction which materially increases the efficiency of the engine to which the manifold is attached; and in general to provide an improved construction of the character referred to.

The invention consists in the matters hereinafter described and more particularly pointed out in the appended claims.

In the drawings—

Figure 1 is a side elevation of a six cylinder gas engine equipped with my invention; Fig. 2 is a top plan view of the same;

Fig. 3 is a vertical sectional view taken on lines 3—3 of Fig. 1, and showing in addition the crank casing.

Fig. 4 is a sectional view of the manifold

taken on lines 4—4 of Fig. 1 and looking in the direction of the arrows.

Referring to the drawings—

1 designates the six cylinders of a gas engine, which in the present instance are shown in Fig. 1 as arranged in pairs. 2 60 designates the crank case, 3 the worm gear casing on which is mounted a worm shaft 4 extending longitudinally of the six cylinders and meshing with the worm wheels 5, there being one of these wheels for each of the six 65 cylinders. These worm wheels are mounted on the lower end of a rotary valve sleeve 6 provided at its upper end with a series of circumferentially extending ports 7 and 8 respectively, and at its lower end with a series of similarly arranged ports 9. These ports coöperate with suitable ports in the cylinder wall. Within the sleeve is a piston 10 connected by piston rod 11 provided with a crank shaft 12 for each of the six cylinders. 75 The particular construction of the rotary valve sleeve and worm gear member however, forms no part of the present invention, being covered in a separate application Serial No. 761,930, and need not therefore be 80 described.

The essence of the present invention resides as heretofore stated in the manifold construction. The inlet manifold 13 communicates with each pair of cylinders by conduits 14 by means of a common chamber 15, in the present instance in the manner shown in the application heretofore referred to. The exhaust manifold 16 communicates directly with each cylinder through a throat 90 or pipe 17, there being one of these pipes 17 for each of the six cylinders. Gas enters the intake manifold 13 through the mouth of the manifold. Gas is discharged from the exhaust manifold through the exhaust opening 95 19, the carburetor (not shown) being secured to the inlet opening 20 by flange coupling 21.

As shown more clearly in Fig. 4, the intake and exhaust manifolds are formed as a single casting. The two manifolds as 100 shown in Fig. 4 are separated by a dividing wall 22 which is shown clearly in Fig. 1 and extends the entire length of the manifolds but curves downwardly toward the central portion as shown at 23, so as to bring 105 all of the exhaust gases past and under the carburetor intake 20. In order to have a more even distribution of the intake gases

the intake manifold 13 is provided opposite the carbureter intake with a deflector plate or flange 24 cast with the manifold, as shown more clearly in Fig. 1. This deflector 24 tends to prevent an excess supply of inlet 5 gas from passing into the center pair of cylinders. It also insures of the inlet gases traveling along the heated wall 22 sufficiently to completely vaporize the inlet 10 gases. The engine may be primed through the priming pipe 25 which is attached to the inlet manifold in the usual way. The gas from the priming pipe passes through an aperture 26 in the deflector plate 24 and is 15 carried into the cylinders.

The operation of the manifolds is as follows:—Assuming that the engine is running, the relatively cool fuel and air after being mixed in the carbureter passes through 20 the inlet 20 into the throat of the inlet manifold 13. This fresh charge passing through the inlet manifold is heated by the hot outgoing exhaust gases and the radiation of the heat units from the latter gases completes 25 the vaporization of the fresh charge of fuel. It is to be noted that this vaporization takes place substantially at the points where the vaporized charge enters the cylinders. Accordingly, the latter does not have 30 an opportunity to become cool or condensed by passing through a relatively cool manifold. At the same time the exhaust gases are cooled by the incoming fresh gases and discharge from the exhaust manifold at a relatively low temperature, thus not only avoiding noise but also tending to prevent 35 back pressure on the cylinders.

I am aware that heretofore attempts have 40 been made to heat the mixture of air and fuel in the carbureter by utilizing some of the heat units from the exhaust gases. None of them however, have effected vaporization of the mixture in the inlet manifold itself. The vaporization of the mixture in the manifold 45 is more effective than in the carbureter even when the latter is more or less heated by the exhaust gases for the reason that the fresh gases are exposed in the present invention to a much larger heating surface than is possible 50 in any carbureter.

The present invention can be readily applied to the great majority of standard types of automobiles without any expensive alteration or reconstruction. It also permits the 55 use of a cheaper and lower grade fuel. This is certainly not feasible in ordinary types of manifolds now in use. This is because a more complete vaporization is obtained in the present invention than is possible in 60 types of carbureters and manifolds now in use.

The present invention resides not only in the broad idea of the manifold construction

shown in the drawings but also consists in the improved method of vaporizing the mixture of fresh fuel so as to effect a complete vaporization of the latter and obviates any tendency to condensation in the manifold. 65

I claim as my invention:—

1. A manifold for multi-cylinder gas engines comprising an exhaust pipe common to all the cylinders, an inlet pipe common to all the cylinders cast integral with and lying wholly without said exhaust pipe, the junction between the two pipes forming a dividing partition between the two pipes substantially equal in length to the length of the inlet pipe, said inlet pipe being provided with a centrally disposed common inlet, and a baffle plate within said inlet pipe whereby 80 the flow of inlet gas between the common inlet and the central pair of cylinders is impeded. 75

2. A manifold for gas engines comprising a main body portion having a circumferentially extending outer wall and a partition wall extending longitudinally through said body portion and dividing the latter into two chambers, forming inlet and exhaust 85 conduits respectively. 90

3. A manifold for multi-cylinder gas engines, comprising a casting generally annular in cross section and having a continuous circumferentially extending outer inclosing wall and a dividing partition extending circumferentially through said casing formed integral therewith and dividing the latter into two separate chambers divided only by said partition wall and forming 95 inlet and exhaust conduits. 100

4. A manifold for multi-cylinder gas engines, comprising a casting generally annular in cross section and having a continuous circumferentially extending outer inclosing wall and a dividing partition extending circumferentially through said casing formed integral therewith and dividing the latter into two separate chambers divided only by said partition wall and forming inlet and exhaust conduits, said partition wall being substantially equal in length to the length of the inlet chamber. 105

5. A manifold for multi-cylinder gas engines, comprising an exhaust pipe common to all cylinders, an inlet pipe common to all 115 cylinders, and a partition wall dividing said pipes, said parts being all cast integral and the inlet and exhaust pipes, each lying in planes parallel with but spaced away from each other except at the juncture formed by 120 said partition wall. 110

MARTIN L. WILLIAMS.
